UNITED STATES PATENT OFFICE.

GUSTAVE H. JANTZ, OF WYOMING, OHIO.

WRINGER ROLL FOR CLOTHES WRINGERS.

Application filed May 12, 1920. Serial No. 380,777.

To all whom it may concern:

Be it known that I, GUSTAVE H. JANTZ, a citizen of the United States, residing at Wyoming, in the county of Hamilton and State of Ohio, have invented certain new and useful Improvements in Wringer Rolls for Clothes Wringers, of which the following is a specification.

Wringer rolls as heretofore constructed comprise a central shaft to which has been affixed, in suitable manner, a cylindrical body of resilient material, such as rubber, the rubber having in practice been laid around the shaft in layers, and then vulcanized so as to fix the rubber and shaft together. Wringer rolls are usually provided with power transmitting means, for instance cog-gears, at the respective ends thereof, and with driving means, for instance a hand-crank, when the wringer is intended for manual operation, or with a suitable cog-gear or cog-gears when the wringer is intended for power actuation, for instance in connection with a power washing machine.

The coating or covering of the wringer roll deteriorates in course of time, and when it has been desired to provide a new wringing surface, it has been found necessary for the user to purchase an entirely new roll, including the power imparting and the power transmitting means thereon, for the reason that, as heretofore constructed, the body of the resilient material or rubber has been permanently vulcanized to the shaft. Shafts of various lengths and with various propelling means thereon have heretofore been made by the different manufacturers of wringers, so that it has been necessary heretofore for the user, if he desired to renew his wringer roll, to obtain an entirely new wringer roll and its attendant parts, comprising driving and transmitting means, from the manufacturer of the particular machine which he has been using.

It is the object of my invention to so construct the wringer roll in novel manner that the resilient surface is provided with a foundation or shell, so that the same may be renewed without the necessity of renewing the working parts connected therewith; further, to provide novel arrangements of shaft-sections and driving connections therefor with the foundation or shell of the wringer roll; further, to provide novel driving arrangements between the proximate

ends of the shaft-sections; and, further, to provide novel supporting means between the sections of the driving shaft and the shell of the wringer roll.

The invention will be further readily understood from the following description and claims, and from the drawings in which latter:

Fig. 1 represents a front elevation of an exemplified wringer, embodying my invention, and adapted to be employed with a power washing machine, parts being broken away and parts being shown in section for better illustration.

Fig. 2 is a similar view of one end of a wringer provided with manual operating means.

Fig. 3 is an axial section of a wringer roll embodying my invention, taken on a line corresponding to the line 3—3 of Fig. 5.

Fig. 4 is an axial section of the same taken on a line corresponding to the line 4—4 of Fig. 5.

Fig. 5 is a cross-section of the same taken on a line corresponding to the line 5—5 of Fig. 3.

Fig. 6 is a cross-section of the same taken on a line corresponding to the line 6—6 of Fig. 3.

Fig. 7 is an axial section, showing a modification of my improved device.

Fig. 8 is a cross-section of the same, taken on a line corresponding to the line 8—8 of Fig. 7.

Fig. 9 is an axial section of a further modification of my improved device.

Fig. 10 is a cross-section of the same taken on a line corresponding to the line 10—10 of Fig. 9.

Fig. 11 is an axial section of another exemplification of my improved device, taken on a line corresponding to the line 11—11 of Fig. 12; and,

Fig. 12 is a cross-section of the same taken on a line corresponding to the line 12—12 of Fig. 11.

My present invention is an extension of the invention shown, described and claimed in my application for patent on improvements in wringer rolls for clothes wringers, filed December 8, 1919, Serial No. 343,322.

The wringer frame is exemplified at 21, and may be of any suitable, usual or desired construction. A wringer roll 22 is arranged to cooperate with a wringer roll 23. The

shaft of the wringer roll 22 is arranged to rotate in bearings 24 in the frame, and the shaft 25 of the wringer roll 23 is arranged to have bearings 26 coact therewith. The 5 bearings 26 are arranged to slide in guide-ways 27 in the frame, pressure means being provided to exert pressure thereon for causing pressure between the rolls when wringing the clothes. A spring 28 may be em- 10 ployed to exert this pressure, being shown adjustable by means of a screw 29, threaded in a bearing 30, on the cross-bar 31 of the frame. I have exemplified my invention as applied to the wringer roll 22 which is the driving wringer roll of the pair, being in 15 practice, the lower wringer roll, but it is intended that both of the wringer-rolls have my invention applied thereto.

Cog-gears 35 are fixed, as by pins 36, to 20 the shaft of the driving wringer roll and are arranged to mesh with cog-gears 37 secured fixedly, as by pins 38, to the shaft of the driven wringer roll. Gear-covers 41, se- 25 cured to the frame, may be provided for the cog-gears and extend over the ends of the resilient portions of the wringer rolls for protecting the same and the clothes which are being operated on.

The shaft of the driving wringer roll is 30 provided with suitable driving means. These driving means may be either power driven or manually operated. I have in Fig. 1 shown the same as power driven means, comprising a driving bevel-gear 46 which meshes with bevel-gears 47, 48, normally loose about the shaft of the driving wringer roll, which is extended for the purpose. Collars 45, fixed by pins 49 to the 35 shaft, hold the bevel-gears 47, 48, in mesh with the bevel-gear 46. A clutch-collar 50 has spline-connection 51 with said shaft and is arranged to be moved lengthwise into neutral position or for engagement of one of the clutches 52, 53, respectively for at-rest 40 position of the wringer rolls, or for driving the wringer rolls in either direction.

I have in Fig. 2 exemplified the shaft of 45 the driving wringer roll provided with a crank-handle 56 of usual construction, se- cured to the shaft of the driving wringer roll by usual means, as by a screw-threaded connection 57 between the hub of the crank- handle and said shaft, and a nut 58 re- 50 ceived over the threaded reduced end 59 of said shaft.

The wringer parts and the operating parts 55 for the wringer rolls may be of usual or ordinary construction, and I have shown and described a usual form of the same as an ex- emplification.

It has been the practice heretofore, when 60 a wringer roll has become worn, to replace the same with a new wringer roll including the driving means thereon, as well as the cog-gears fixed thereto, for the reason that

wringer rolls, as heretofore constructed, have been built up as integral structures including the central shaft, the resilient material vulcanized thereon, the cog-gears on the shaft, as well as power driving means 70 thereon or the securing means thereon for the crank-handle when a crank-handle is employed, or other driving and power trans- mitting means which may be employed.

In my improved construction I mount the 75 resilient clothes contacting portion of the wringer roll, exemplified at 60, on a releas- able foundation or shell, so that this releas- able foundation or shell with its resilient 80 covering, may be replaced by a fresh or new 85 releasable foundation or shell with its re- slient covering without the necessity of re- placement of the shaft, the cog-gears, or the driving or power transmitting means. Ex- 90emplifying such construction, I provide a 95 shell 61, which is shown as an integral shell, although the same may be made pluri-part in any suitable manner, for instance as shown, described and claimed in my afore- said pending application. The shell is pro- 95 vided at each end thereof with a collar 62, and at an intermediate point of its interior with a collar 63, these collars being prefer- ably in alinement.

I prefer to provide a shaft comprising a 95 plurality of shaft-sections, exemplified at 65, 66. The respective shaft-sections are pro- vided with the driving means or power transmitting means, such as may be em- 100 ployed, for instance with the cog-gears 35 fixed thereto, one of the shaft-sections being also provided with the driving means, when the driving means are employed on the shaft.

The respective shaft-sections are prefer- ably received into the shell through oppo- 105 site ends of the latter, and the proximate ends of the shaft-sections are provided with coacting parts to cause driving relation be- 110 tween the shaft-sections, these driving rela- tions being preferably located within or ad- jacent to the inner collar in the shell, in order that the inner collar may aid in the cor- 115 rect positioning of the proximate ends of the shaft-sections, the proper locking rela- tion of the proximate ends of the shaft-sections and in the proper maintenance of ax- 120 ial relation between the shaft-sections and the shell.

The driving connections between the 120 shaft-sections preferably include overlap- ping proximate ends of the shaft-sections. Thus in Figs. 3 to 6 inclusive, I have shown the inner proximate ends of the shaft-sections provided with interengaging tongues 125 71, 72, the tongues 72 forming a groove 73 between them for the reception of the tongue 71. The proximate ends of the shaft are received endwise in the inner collar 63 of the shell. The end-collars position the 130

outer ends of the shaft-sections, all the collars acting to maintain the shaft-sections in alinement.

The construction is preferably such that 5 round shaft-sections may be employed, the walls of the collars being preferably round to correspond with the cross-sectional form of the shaft-sections. Pins 75 may be received through the ends of the shell and the respec-

10 tive shaft-sections for securing the shaft-sections and the shell together, these pins being preferably taper pins, which may be readily driven out in usual manner for releasing the shaft-sections from the shell.

15 Circumferential spaces 77 are preferably located circumferentially between the shaft-sections and the shell, lengthwise of the shaft-sections, between the collars in the shell. The shaft-sections therefore prefer-

20 ably make contact with the shell only at the collars. The interior collar maintains the axial relation between the inner or proximate ends of the shaft-sections and maintains the shaft-sections in axial alinement,

25 and, furthermore, prevents lateral displacement between the proximate ends of the shaft-sections in order to maintain the locking relation between them.

Other forms of connections between the 30 inner ends of the shaft-sections may be employed. I have shown a modification in Figs. 7 and 8, in which each of the shaft-sections has one of its sides removed lengthwise thereof, for forming rabbets 81, and 35 tongues 82 received in the rabbets, and forming proximate faces 83 on said tongues extending lengthwise of the tongues and shaft-sections, to form driving relation between the shaft-sections in conjunction with the 40 inner wall of the inner collar.

A further modification is shown in Figs. 9 and 10, in which the inner end of one of the shaft-sections is provided with a tongue 85, exemplified as polygonal in cross-section, 45 received in a corresponding and coacting socket 86, in the inner end of the other shaft-section. The proximate ends of the shaft-sections are further supported by the inner collar in the shell.

50 The shell is preferably made of metal, forming a foundation for the resilient body 60 of the shell, preferably vulcanized thereon in any ordinary or usual manner.

The shaft-sections are preferably inserted 55 into the shell after completion of the releasable wringer-roll thus formed, the inner ends of the shaft-sections being placed in coactive relations and positioned in lateral directions by the inner collar. The ends of 60 the inner collar are tapered inwardly, as shown at 87, and the inner ends of the shaft-sections are tapered, as shown at 88, 89, in Figs. 3 and 4, at 91, 92, in Figs. 7 and 8, and at 93, 94, 95, in Figs. 9 and 10, to permit 65 ready assembling of the parts. The pins 75

may then be inserted for connecting the shell and the shaft-sections together, and for aiding and rotatively securing the shaft-sections and the releasable wringer roll together, and fixing the shaft-sections endwise 70 with relation to the wringer roll, when the shaft-sections are in place. The axes of rotation of the shaft-sections and of the shell are coincident.

When it is desired to renew the releasable 75 wringer roll in my improved device, the pins 75 are removed and the shaft-sections are withdrawn endwise out of the shell, a new releasable wringer roll being substituted for the worn releasable wringer roll. The shaft-sections and new releasable wringer roll are assembled in the manner hereinbefore described.

In order to facilitate release between the shaft-sections and the shell, the shaft-sections have their proximate ends so disposed that one of the shaft-sections may be employed to drive the other of the shaft-sections endwise to release its connection with its bearings for ready removal of the same. 85 The provision of the circumferential spaces about the shaft-sections between the bearings in the shell reduce the danger of the shaft-sections becoming fixed, as by rust, in 90 the shell.

95 My improved construction further provides extreme strength in the middle of the roll, where the greatest pressures on rolls of this character are directed, for the reason that the inner collar forms strengthening means or strengthening rib for the shell and acts further to strengthen the shaft and maintain the shaft-sections in coincident axial alinement. The provision of the 100 spaces between the bearings prevents the 105 rusting in of the shaft-sections.

I have in Figs. 11 and 12 shown a form 110 of my invention embracing the shell provided with a resilient covering, the shell being provided with the end-collars and the intermediate collar hereinbefore described, and with the intermediate circumferential spaces therebetween, an integral shaft 97, provided with the driving means and motion transmitting means, being received 115 through the shell and through said collars, and having support in each of said collars, and spaced from the inner wall of the shell between the collars for ready endwise removal of the shaft, in case this might be 120 desired. The ends of the shell are secured to the shaft by means of taper pins 98, and the cog-gears 35 are secured to the shaft by taper pins 99. The pins may be readily removed, if it is desired to renew the releasable 125 wringer roll.

Having thus fully described my invention, what I claim as new, and desire to secure by Letters Patent, is:

1. In a wringer roll for a clothes wringer,

- the combination of a shell, and shaft-sections having inner ends received in said shell, said inner ends having means to lock them against relative rotation by axial movements between said inner ends, said shell provided with inner end collars for the respective outer ends of said shaft-sections and with an inner collar for the inner ends of said shaft-sections.
- 10 2. In a wringer roll for a clothes wringer, the combination of a shell provided with a resilient covering forming a releasable wringer roll, and a shaft comprising shaft-sections in said shell, the inner ends of said shaft-sections having overlapping means to lock them against relative rotation brought into rotative driving engagement by axial movements between said shaft-sections, and an inner collar in said shell at said inner ends of said shaft-sections to maintain said inner ends of said shaft-sections in axial alinement with each other, whereby to maintain said overlapping inner ends in operative relation with each other.
- 15 3. In a wringer roll for a clothes wringer, the combination of a shell provided with a resilient covering for forming a wringer roll, and a shaft comprising a plurality of shaft-sections in said shell, the inner ends of said sections of said shaft having means to lock them against relative rotation whereby to form a mating driving connection between them by axial movement between said sections, said shell adjacent to said driving connection provided with a collar for said shaft-sections to maintain said inner ends in axial alinement with each other, said shell at the respective ends thereof provided with collars for the outer ends of said shaft-sections, and the said shaft-sections being circumferentially spaced from the inner wall of said shell between said first-named collar and each of said last-named collars.
- 20 4. In a wringer roll for a clothes wringer, the combination of a shell provided with a resilient covering, and shaft-sections extending into the interior of said shell to points proximately in the middle of said shell, the said shell proximate at said middle provided with an interior collar, and the inner ends of said shaft-sections provided with overlapping parts in said interior collar brought into locking engagement by axial movement between said shaft-sections.
- 25 5. In a wringer roll for a clothes wringer, the combination of a shell provided with a resilient covering, said shell provided with an inner collar intermediate of its ends and with inner end collars, a shaft received through said collars, said collars maintain-

ing said shell on said shaft so that the axes of rotation of said shell and said shaft remain coincident, there being circumferential space about said shaft extending lengthwise of said shaft between said shaft and the inner wall of said shell and between said intermediate inner collar and each of said end collars, and releasable securing means between said shell and said shaft.

6. In a wringer roll for a clothes wringer, the combination of a shell, shaft-sections received in the respective ends of said shell, and collar means in said shell for the inner ends of said shaft-sections, the inner ends of said shaft-sections and the supporting parts of said collar means so formed that one of said shaft-sections is arranged to move the other of said shaft-sections endwise in said collar means, and one of said shaft sections provided with driving means whereby to rotate said shaft-sections and said shell.

7. In a wringer roll for a clothes wringer, the combination of a shell, a pluri-part shaft comprising shaft-sections extending into said shell, said shell at its respective ends provided with inner end collars and at an intermediate point in the interior thereof provided with an intermediate collar for said shaft-sections and circumferential spaces extending lengthwise of said shaft-sections in the interior of said shell between said intermediate collar and said respective inner end collars and located circumferentially between said shaft-sections and the inner wall of said shell.

8. In a wringer roll for a clothes wringer, the combination of a shell provided with a cylindrical resilient covering and with inner end collars and an intermediate collar, said shell provided with recesses forming bores of greater diameters than the diameters of the inner walls of said collars, one of said recesses located between said intermediate collar and each of said inner end collars, and releasable shaft-sections, one of said releasable shaft-sections extending throughout each of said recesses, said releasable shaft-sections located in said intermediate collar and in said respective inner end collars, said bores forming spaces about said respective shaft-sections between said intermediate collar and said respective inner end collars.

In testimony whereof, I have hereunto signed my name in the presence of two subscribing witnesses.

GUSTAVE H. JANTZ.

In presence of—
DELMA WUNSING,
JAMES J. FITZPATRICK.
